US0D1040868S

(12) **United States Design Patent** (10) **Patent No.:** **US D1,040,868 S**
(45) **Date of Patent:** **** Sep. 3, 2024**

(54) **RETENTION COMPONENT**

(71) Applicant: **CATERPILLAR INC.**, Peoria, IL (US)

(72) Inventors: **William Jay Ulrich, IV**, East Peoria, IL (US); **Eric Thomas Sinn**, East Peoria, IL (US); **Corey M. Wells**, East Peoria, IL (US); **Brandon H. McCaffrey**, Saint Louis, MO (US); **Doug Serrurier**, Morton, IL (US); **David B. Parzynski, Jr.**, Peoria, IL (US)

(73) Assignee: **Caterpillar Inc.**, Peoria, IL (US)

(**) Term: **15 Years**

(21) Appl. No.: **29/865,110**

(22) Filed: **Jul. 8, 2022**

(51) LOC (14) Cl. **15-03**

(52) U.S. Cl.

USPC **D15/28**; D8/349

(57) **CLAIM**

The ornamental design for a retention component, as shown and described.

DESCRIPTION

FIG. 1 is a front, top, right perspective view of a retention component;

FIG. 2 is a front, bottom, left perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

1 Claim, 8 Drawing Sheets
